(57) **CLAIM**

The ornamental design for an optic, as shown and described.

DESCRIPTION

FIG. 1 is a perspective view of the optic;

FIG. 2 is a perspective view of the optic of FIG. 1 from a second viewing angle;

FIG. 3 is an enlarged section view taken at inset circle 3 in FIG. 2;

FIG. 4 is a perspective view of the optic of FIG. 1 from a third viewing angle;

FIG. 5 is an enlarged section view taken at inset circle 5 in FIG. 4;

FIG. 6 is a top plan view of the optic of FIG. 1;

FIG. 7 is a rear elevation view of the optic of FIG. 1;

FIG. 8 is a right side elevation view of the optic of FIG. 1;

FIG. 9 is a front elevation view of the optic of FIG. 1;

FIG. 10 is a left side elevation view of the optic of FIG. 1;

FIG. 11 is a bottom plan view of the optic of FIG. 1;

FIG. 12 is a perspective view, of the optic of FIG. 1, installed within a luminaire;

FIG. 13 is a top plan view of the optic within the luminaire of FIG. 12;

FIG. 14 is a rear elevation view of the optic within the luminaire of FIG. 12;

FIG. 15 is a right side elevation view of the optic within the luminaire of FIG. 12;

FIG. 16 is a front elevation view of the optic within the luminaire of FIG. 12;

FIG. 17 is a left side elevation view of the optic within the luminaire of FIG. 12; and,

FIG. 18 is a bottom plan view of the optic within the luminaire of FIG. 12.

Features shown in evenly dotted broken lines illustrate portions of the optic that form no part of the claimed design.
